UNITED STATES PATENT OFFICE.

DONALD F. WARNER, OF LYNN, AND FRANKLIN R. ERICSON, OF BEVERLY, MASSACHUSETTS, ASSIGNEES TO GENERAL ELECTRIC COMPANY, A CORPORATION OF NEW YORK.

REGULATING MEANS FOR ELASTIC-FLUID TURBINES.

Application filed January 27, 1928. Serial No. 250,054.

The present invention relates to elastic fluid turbines and especially to elastic fluid turbines wherein elastic fluid is extracted from an intermediate stage for industrial purposes and wherein also the exhaust elastic fluid from the turbine is utilized for industrial purposes. In said turbines, it is desirable to control the admission of elastic fluid to the turbine and the flow of elastic fluid from the extraction stage to the next lower stage in response to a condition appurtenant to the elastic fluid flowing in the extraction conduit and in response to a condition appurtenant to the elastic fluid flowing from the exhaust conduit, the regulation of the elastic fluid being independent of the speed governor. The more usual application is that of controlling the admission of elastic fluid to the turbine and the flow of elastic fluid from the extraction stage to the next lower stage in terms of the extraction stage pressure and of the exhaust pressure. In other words, to so control the flow of elastic fluid to the turbine and the flow from the extraction stage to the next lower stage as to maintain both the extraction stage pressure and the exhaust pressure substantially constant, we have accordingly illustrated our invention as utilized in this particular manner. It is to be understood, however, that it is not limited thereto necessarily.

In connection with such turbines, which may be termed extraction back pressure turbines, it is the practice to fix the speed of the turbine by some means other than its speed governor. The usual method in the case of alternating current turbo-generator sets is to tie the alternating current generator which the turbine drives, to an alternating current system the frequency of which is fixed by other turbo-generators connected to the same system. The extraction back pressure turbine therefore is maintained by external means at a constant speed and utilizes an amount of elastic fluid sufficient to supply the demand for elastic fluid for the industrial purposes associated with the extraction conduit and the exhaust conduit. In connection with such turbines the usual speed governor functions as a pre-emergency governor being set for a speed higher than the normal turbine speed but somewhat below that for which the emergency governor is set.

The object of our invention is to provide an improved regulating mechanism for an

elastic fluid turbine of the above type, and for a consideration of what we believe to be novel and our invention, attention is directed to the accompanying description and the claims appended thereto.

60

The drawing is a diagrammatic view partly in section of an elastic fluid turbine provided with regulating means embodying our invention.

Referring to the drawing, 1 indicates the 65 casing of an elastic fluid turbine, 2 indicates the shaft, and 3 indicates one of the bucket wheels. The turbine is illustrated as being viewed from the high pressure end and is partly broken away at different sections to 70 bring out diagrammatically the arrangement. 4 indicates a conduit for admitting elastic fluid to the high pressure end of the turbine, the admission of elastic fluid being controlled by a valve means 5. 6 indicates the exhaust- 75 conduit for the turbine and 7 indicates an extraction conduit connected to an intermediate stage of the turbine which may be termed the extraction stage. In the extraction stage is a valve means 8, a known form of ring valve 80 being illustrated, which serves to control the flow of elastic fluid from the extraction stage to the next lower stage. It is provided with a gear segment 9 with which meshes a short rack 10 connected by a rod 11 and to the piston 12 of a fluid-actuated motor. The pilot valve for the fluid-actuated motor is indicated at 13. When ring valve 8 is turned in a clockwise direction it serves to shut off the flow of elastic fluid from the extraction stage 90 to the next lower stage while when it is turned in a counter clockwise direction it is opened further to permit of increase in the flow of elastic fluid from the extraction stage to the next lower stage. The ring valve is illustrated 95 diagrammatically and by way of example, such arrangements being now known in the art. A valve means of this type is more particularly illustrated and described in the patent to Norton, 1,091,078, dated March 24, 1914. 100

The construction so far described is to be taken as typical of any suitable elastic fluid turbine having valve means for regulating the admission of elastic fluid to the turbine, a conduit connected to an intermediate stage 105 of the turbine, and a valve means for controlling the flow of elastic fluid from such intermediate stage to the next lower stage.

In carrying out our invention and in accordance with the embodiment thereof il- 110

lustrated in the drawing, we provide means responsive to the exhaust pressure which, upon a change of the exhaust pressure, serves to adjust the position of both the admission 5 valve means and the extraction stage valve means, and which upon a change in the extraction stage pressure, adjusts the admission valve means only. By this arrangement we find that we are enabled to regulate the elastic 10 fluid turbine in terms of both the extraction stage pressure and the exhaust pressure and maintain both such pressures substantially constant.

14 indicates a pressure responsive device 15 here shown as being in the form of a corrugated bellows located in a casing 15. Casing 15 is connected by a pipe 16 to exhaust conduit 6. Pressure responsive device 14 is thus subjected to the exhaust conduit pressure.

20 Connected to the pressure responsive device is a stem 17 which at its upper end is connected to one end of a floating lever 18. The other end of lever 18 is connected to a speed governor 19 driven from the turbine shaft.

25 In view of the diagrammatic nature of the drawing, the speed governor is not shown in correct relation to the turbine shaft. It will be understood, however, that any suitable arrangement may be used.

30 Spring 21 is a tension spring and operates in a direction to oppose the collapsing of corrugated bellows 14. The tension of the spring may be adjusted by turning the nut 20 in sleeve 20^a. When the pressure in exhaust

35 conduit 6 increases corrugated bellows 14 is collapsed somewhat moving the left hand end of lever 18 upward, while when the pressure decreases spring 21 serves to lower the left hand end of lever 18. Lever 18 is connected 40 by a link 22 to one end of a lever 23 pivoted on a fixed fulcrum 24. Pivoted mounted on lever 23 is a bell crank lever comprising arms 25 and 26. Arm 25 is connected by a link 27 to one end of a lever 28. The other end 45 of lever 28 is connected to a suitable fulcrum 29.

Lever 28 is connected by a link 30 to one end 50 of a floating lever 31. The other end of floating lever 31 is connected to the stem 32 of a fluid-actuated motor 33, the stem 34 of the pilot valve of the fluid-actuated motor being connected to floating lever 31 at an intermediate point. The stem 32 is connected to a valve disk 35 of valve means 5. This 55 forms a known arrangement of fluid-actuated motor for actuating a valve means, the arrangement including a usual form of follow-up connection. The arrangement is to be taken as typical of any suitable turbine valve means and fluid-actuated motor for moving the same.

60 Lever 23 is connected by a rod 36 to one arm of a bell crank lever 37 pivoted at the end of a bracket 38, the other arm being connected to one end of a floating lever 39. The other end

of floating lever 39 is pivotally connected to a lever arm 40 pivoted at its lower end on bracket 41 and pivotally connected at its upper end to a rod 42 which forms an extension of piston rod 11. The stem of pilot valve 13 is connected to floating lever 39. These connections form a known arrangement of actuating means including a follow-up connection for effecting movement of ring valve 8 through the intermediary of the fluid-actuated motor.

65 Bell crank lever arm 26 is connected by a link 43 to one arm of the bell crank lever 44 pivoted to lever 23 in line with its pivot 24. The other arm of bell crank lever 44 is pivotally connected to a stem 45 which at its lower end is connected to a corrugated bellows 46 similar to the corrugated bellows 14. Corrugated bellows 46 is located in a casing 47 which is connected by a pipe 48 to the extraction stage conduit 7. Corrugated bellows 46 is thus subjected to the pressure in the extraction stage. The collapsing of corrugated bellows 46 is opposed by an adjustable tension spring 49 arranged in a manner similar to the 90 spring 21.

70 The operation is as follows:

75 Assume that the turbine is running, the speed being fixed by some external means and that valve means 5 and ring valve 8 are positioned so that the pressures in the extraction stage conduit and the exhaust conduit are of the desired value. If now the pressure in the exhaust conduit increases, for example, corrugated bellows 14 will be collapsed somewhat thereby lifting the left hand end of lever 18 and through link 22 lifting the left hand end of lever 23, the lever 23 turning on its pivot 24. This serves to lift the right hand end of lever 28 thereby lifting the pilot valve 100 of fluid-actuated motor 33 so as to admit actuating fluid to the upper side of the piston of the fluid-actuated motor and permitting it to escape from the lower side. This causes the piston to move downward thereby closing 110 valve means 5 somewhat so as to decrease the amount of elastic fluid being admitted to the turbine. When the piston of the fluid-actuated motor moves downward it lowers the right hand end of floating lever 31 thereby 115 restoring the pilot valve to its former position. Also, when lever 23 moves upward, through rod 36 it turns bell crank lever 37 moving pilot valve 13 toward the left. This serves to admit actuating fluid to the left 120 hand side of piston 12 and permits it to escape from the right hand side thereby moving piston 12 toward the right and effecting a closing movement of the ring valve 8. When piston 12 moves toward the right the pilot 125 valve is restored to its former position through lever arm 40 and the floating lever connection 39. If the pressure in exhaust conduit 6 decreases then spring 21 effects 130 downward movement of the left hand end of

135

lever 18 and in a manner similar to that already described, effects an opening movement of valve means 5 and of the ring valve 8. Thus it will be seen that when the exhaust conduit pressure increases both the high pressure valve means and the ring valve means are closed somewhat, while when the exhaust conduit pressure decreases both the high pressure valve means and the ring valve means are opened somewhat.

The pressure in the extraction stage is maintained substantially constant as a result of the movements of both the admission valve means and the ring valve means, such motion resulting from increase or decrease in the exhaust pressure due to changes in demand for elastic fluid.

In connection with the operation of the mechanism it will be understood that the lever 20 arm and the connections are so chosen relatively to each other that when lever arm 23 is moved valve means 5 and valve means 8 are opened or closed by amounts such that valve means 8 will effect an increase or decrease of flow past it corresponding to the change in flow past valve means 5.

If the pressure in the extraction stage conduit increases, bellows 46 is collapsed somewhat thereby turning bell crank lever 44 in a clockwise direction and through link 43 turning the bell crank lever comprising arms 25 and 26 in a clockwise direction. This serves to lift the pilot valve of fluid-actuated motor 33 thereby effecting a closing movement of the valve means 5 to decrease the amount of elastic fluid admitted to the turbine and bring the pressure in the extraction stage back to its equilibrium value, which is substantially its former value. If the pressure in the extraction stage decreases then spring 45 serves to turn bell crank lever 44 in a counter clockwise direction, thereby effecting an opening movement of valve means 5 so as to restore the pressure to its equilibrium value. When the pressure in the extraction stage varies, it will be seen that no adjustment of the stage valve means takes place, the high pressure valve means only being moved to bring the extraction stage pressure back to normal value. As a result the pressure in the exhaust conduit will not be disturbed.

It will be seen that by our invention, we are enabled to maintain substantially constant the pressure in both the extraction stage conduit and the exhaust stage conduit.

The speed governor 29 is set for a speed a predetermined amount higher than the normal turbine speed and forms what is termed 60 usually a pre-emergency governor. It acts upon both the admission valve means 5 and the extraction valve means 8. Normally it performs no function. It comes into action to take control of the turbine only in case for 65 some reason the speed of the turbine exceeds

by a predetermined amount its normal speed.

In accordance with the provisions of the patent statutes, we have described the principle of operation of our invention, together with the apparatus which we now consider to represent the best embodiment thereof, but we desire to have it understood that the apparatus shown is only illustrative and that the invention may be carried out by other means.

What we claim as new and desire to secure by Letters Patent of the United States, is,—

1. The combination with an elastic fluid turbine having a conduit connected to an intermediate stage, valve means controlling the flow of elastic fluid to the turbine, and valve means controlling the flow of elastic fluid from said intermediate stage to the next lower stage, of means responsive to a condition appurtenant to the exhaust leaving the turbine 80 for effecting adjustment of both said valve means in the same direction and means responsive to a condition appurtenant to elastic fluid flowing in said conduit for effecting adjustment of said first-named valve means 90 only.

2. The combination with an elastic fluid turbine having a conduit connected to an intermediate stage, valve means controlling the flow of elastic fluid to the turbine and valve means controlling the flow of elastic fluid from said intermediate stage to the next lower stage, of means responsive to the exhaust pressure for effecting adjustment of both said valve means in the same direction and means responsive to the pressure in said conduit for effecting adjustment of said first-named valve means only.

3. The combination with an elastic fluid turbine having a conduit connected to an intermediate stage, valve means controlling the flow of elastic fluid to the turbine and valve means controlling the flow of elastic fluid from said intermediate stage to the next lower stage, of a lever, means connecting both said valve means to said lever whereby when said lever is moved both valve means are adjusted in the same direction, means responsive to a condition appurtenant to the exhaust leaving the turbine for moving said lever, and means responsive to a condition appurtenant to elastic fluid flowing in said conduit for effecting adjustment of said first-named valve means independently of said lever.

4. The combination with an elastic fluid turbine having a conduit connected to an intermediate stage, valve means controlling the flow of elastic fluid to the turbine and valve means controlling the flow of elastic fluid from said intermediate stage to the next lower stage, of a lever, a second lever fulcrumed on said first-named lever, means connecting said first-named lever to said second-named valve means, means connecting said second-named lever to said first-named valve means,

means responsive to a condition appurtenant to the exhaust leaving the turbine for moving said first-named lever whereby both said valve means are adjusted and means responsive to a condition appurtenant to elastic fluid flowing in said conduit for moving said second-named lever only whereby said first-

named valve means is adjusted independently of said second-named valve means.

In witness whereof, we have hereunto set ¹⁰ our hands this 24th day of January, 1928.

DONALD F. WARNER.
FRANKLIN R. ERICSON.
